UNITED STATES PATENT OFFICE

JAMES L. DE VOU, OF PITTSBURGH, PENNSYLVANIA

ERCTION APPARATUS

Application filed March 19, 1932. Serial No. 600,037.

This invention relates to an erection apparatus, one of the objects being to provide a means for unloading, handling and erecting structural steel. Another object is to provide a mobile self-propelled unit which may be adapted to a variety of uses in the construction of steel structures. Other objects will be understood from the following disclosure.

10 Having reference to the accompanying drawings, which illustrate a specific form of the new erection apparatus:

Figure 1 is a side elevation.

15 Figure 2 is a top plan with the lifting apparatus removed.

Figure 3 is an end elevation of Figure 2.

Figures 4, 5 and 6 are enlarged cross-sectional details.

20 Figures 7 and 8 are respectively top plan and side elevations of the apparatus in operation.

These drawings show an elongated frame 1 consisting of two sliding sections bolted together through a plate 2 whereby the frame's length may be varied. A number of rollers 3 are laterally spaced along the top of this frame and are each provided with wedges 4 which may be moved tightly against them by a lever 5 so as to lock them against rotation. A declined runway 6, which may swing upwardly on a pin 7, is fixed to one end of the frame 1. A set of rolling units 8 is fixed under the frame 1 at the end carrying the runway 6 and another set 9 is swiveled under the other end of this frame. These rolling units may be of any character, the illustrations showing them in caterpillar form so that the apparatus may be used on soft or rough ground.

40 A mobile self-driven power unit 10 is fixed on the frame 1 adjacent its runway by clamps 11. To prevent the weight of this unit injuring the rollers 3 blocks 12 are preferably placed beneath it, and the runway 6 has a raised portion 13. This power unit includes a plurality of cable drums 14 and a power take-off 15. This take-off is connected through a chain 16 to a shaft 17 which in turn drives the rolling unit 8 through a chain 18. This shaft is geared to a second shaft 19

which drives a pair of drums 20 through clutches 21. Cables 22 connect these drums to swing the swiveled rolling units 9.

The other end of the frame 1 carries a hoisting rig consisting of a stiff A-frame strut 23 and a boom 24. This rig is fixed to the frame by pins 25 so that it may easily be demounted. Its various operating cables 26 are fixed to the drums 14 of the power unit 10. Of course, these drums are all provided with clutches and brakes of the usual type which may be selectively operated by a plurality of levers 27. The clutches 21 may also be provided with suitable connections 28 to the levers 27 so that the entire unit may be operated from one point. Preferably the frame 1 is provided with jacks 29 which carry the load while the hoisting rig is being used.

70 One of the advantages of the apparatus just described is that it obviates the necessity of running track extensions from a railway siding to a job. Assuming that the structural steel is on cars at a railway siding and that the point where they are to be erected is some distance away, the apparatus is driven to the railway siding where the boom 24 is lowered to the ground and disconnected from the frame 1, after which the stiff A-frame strut 23 is also demounted. The power unit 10 is then unclamped from the frame 1 and driven down the runway 6 to the ground. The hoisting rig is then set up adjacent the car in the usual manner (Figure 7) and its cables, which were disconnected from the drums 14 during the demounting operation, are reconnected thereto. By the use of this hoisting rig a number of the structural steel sections are transferred to the frame 1. The cables 26 are then disconnected from the drums 14 of the power unit 10 and this unit is hitched to the swiveled rolling units 9 (Figure 8) through a draw-bar 30. By this means these loaded sections are transported to the point where they are to be erected. Rough ground will not interfere with the progress of the apparatus because of its rugged character, the runway 6 swinging upwardly on the pin 7 whenever it strikes an obstruction, and thus remaining undamaged.

When the point of erection is reached the lever 5 is operated to unlock the rollers 3 so that the structural sections may be run off the frame 1 and down the runway 6 to the ground without damage. The apparatus is then driven back to the pile of structural steel sections and the foregoing operation repeated until all have been transported to their point of erection. The power unit 10 is then reinstalled on the frame 1, the stiff A-frame strut 23 remounted and, with the latter's aid, the boom 24 remounted. The various cables 26 are reconnected to the drums 14 and the chain 16, which was of course removed when the power unit 10 was demounted, replaced. The apparatus is then driven to the job and used as a mobile crane to erect the steel sections.

It will be seen from the foregoing that the apparatus is at all times a mobile self-driven unit which is extremely flexible in its operation and which may be adapted to a variety of uses. The power unit, the hoisting rig and the truck produce a coacting combination of great usefulness and adaptability.

Although a specific form of this apparatus has been shown and described in accordance with the patent statutes, it is not intended to limit the scope of the invention exactly thereto, except as defined by the following claims.

I claim:

1. An erection apparatus including an elongated frame, a set of rolling units fixed under one end of said frame, a set of rolling units swiveled under the other end of said frame, a mobile self-driven power unit on said frame adjacent said fixed rolling units constructed with a plurality of cable drums and a power take-off, means for connecting said take-off to said fixed rolling unit, means including clutches for connecting said take-off to swing said swiveled rolling units and a cabled hoisting rig demountably fixed to said frame adjacent said swiveled rolling units with its operating cable arranged for connection with said cable drums.

2. An erection apparatus including an elongated frame, a plurality of rollers spaced laterally along the top of said frame, means for locking said rollers against rotation, a declined runway at one end of said frame, a fixed set of rolling units under the runway end of said frame, a swiveled set of rolling units under the other end of said frame, a mobile self-driven power unit on said frame adjacent its runway and constructed with a plurality of cable drums and a power take-off, means for connecting said take-off to said fixed rolling unit, means including clutches for connecting said take-off to swing said swiveled rolling units and a cabled hoisting rig demountably fixed to said frame adjacent said swiveled rolling units with its operating cables arranged for connection with said cable drums.

3. A construction apparatus including an elongated frame constructed and arranged so that its length may be varied, a plurality of rollers spaced laterally along the top of said frame, means for locking said rollers against rotation, a declined runway constructed and arranged at one end of said frame for vertical swinging movement, a fixed set of rolling units under the runway end of said frame, a swiveled set of rolling units under the other end of said frame, a mobile self-driven power unit removably clamped on said frame adjacent its runway constructed with a plurality of cable drums and a power take-off, means for connecting said power take-off to drive said fixed set of rolling units, means including clutches for connecting said take-off to swing said swiveled set of rolling units and a cabled hoisting rig demountably fixed to said frame adjacent said swiveled rolling units with its operating cables arranged for connection to said cable drums.

In testimony whereby, I have hereunto set my hand.

JAMES L. DE VOU.
